RECIPROCATING CARRIAGE MOTION

Sten Richard Stenstrom, Trollhattan, Sweden

Application October 31, 1955, Serial No. 543,801

1 Claim. (Cl. 74—27)

This invention relates to improvements in the drive and drive-control of the type-beds of printing presses of the two-revolution type.

An object of this invention is to secure absolute register between the type and sheet being printed by exact control of the speed of movement of the type-bed while engaged with the impression cylinder of the press.

According to this invention a printing press, for instance, a two-revolution press, having a reciprocating type-bed, is provided which, during the printing and return periods, is arranged for being driven by racks attached to the type-bed, alternately engaging in driving shuttle wheels, and which during retardation and acceleration periods at the end positions is arranged to receive its motion by means of turning forks made in one piece and attached to the movable type-bed, cooperating with swingable arms fitted with rollers, these rollers entering grooves limited by the legs or shanks of the forks. In presses of the two-revolution type, the impression cylinder rotates two turns during a complete printing operation, during which time six different periods of motion can be discerned for the reciprocating type-bed, as follows:

- I. Printing period, during which the type bed has constant speed
- II. Retardation period (with stop and reverse)
- III. Acceleration period
- IV. Return period (at constant speed)
- V. Retardation period (with stop and reverse)
- VI. Acceleration period.

During the printing period, an absolutely constant type-bed synchronous with the peripheral velocity of the impression cylinder is required, in order to secure exact register. Previously, considerable difficulties were encountered in attempting to attain uniform running, and consequently a perfect print. These difficulties have been entirely overcome by the present invention, while at the same time the dimensions of the press can be reduced considerably.

The invention is mainly characterized in that the fork grooves individually are straight in their interior part and become wider towards their outer part, owing to the fact that this partly groove-limiting part of each of the two fork legs is shaped as a curve, the curve center and curve radius of which differ from those of the arc belonging to the other fork leg portion.

In the accompanying drawings an embodiment of the invention is represented by way of example.

In the drawings—

Figure 1 is a side view of a press according to this invention;

Figure 2 is a transverse vertical sectional view on the line II—II of Fig. 1;

Figure 3 is a plan view of the elements associated with the inner frame, with the type-bed removed, and the outer frame omitted;

2

Figure 4 is a diagrammatic representation of the drive of a swingable arm used for controlling the type-bed of the press in its end position; and

Figure 5 is an enlarged diagrammatic sectional view illustrating the shape of the turning fork of the drive.

In the accompanying drawings reference numeral 1 designates a side of the main stand or frame of the press while the other side portion of the main frame is designated by numeral 2. Numerals 3 and 4 indicate the end portions respectively of the main frame. Within the main frame is located an inner frame, the two side portions of which are indicated by 5 and 6, respectively. The principal mechanism for operating the reciprocating type-bed of the press is mounted in or associated with the inner frame 5, 6. Extending transversely through one side portion 6 of the inner frame and through side portion 1 of the main frame is a drive shaft 7 having one end portion, outside of the main frame wall 1, a main driving wheel 8, illustrated as a gear but which obviously could be a pulley.

The driving power for operating the type-bed, supplied to the press through gear wheel 8 and shaft 7, is transmitted through gear wheel 10, mounted on shaft 7 to two gear wheels 11, 12, which are in mesh with each other. Gear wheels 11 and 12 are mounted on transversely extending shafts 14 and 15 respectively, carried by inner frame walls 5 and 6. Gear wheel 11 is in mesh with a shuttle wheel 16, and gear wheel 12 with shuttle wheel 17. The shuttle wheels 16 and 17 are mounted on shafts 19 and 20, respectively, and are slidable sideways on said shaft. This sidewise motion of the shuttle wheels 16 and 17 is obtained from two two-armed levers 21 and 22, which are pivotally mounted on brackets 25 and 26, respectively, intermediate of their ends. The upper ends of the levers are provided with laterally extending forks 23, 24, respectively, which engage in slots 18, 18' of shuttle wheels 16, 17, respectively, and serve to slide the shuttle wheels laterally of the press upon action of levers 21, 22, by mechanism to be described.

In the lower portion of the main frame and of the inner frame of the press is mounted a transversely extending shaft 27, having a driving gear wheel 28 mounted thereon. Gear wheel 28 meshes with and is driven by gear wheel 29 fixedly mounted on transversely extending shaft

45 14 on the other end of which is mounted gear wheel 11. Shaft 27 is thus provided with intermittent turning motion, and is provided with a cam 31 which turns therewith. The end portions 34 and 35, respectively, of two-armed levers 21 and 22 are arranged to engage with and be operated in an intermittent reciprocatory motion by roller 36 operatively connected with cam 31 by means of link 37 and linkage bolts 38, 38', respectively.

The arrangement or system is such that, when the press is running, the type-bed 39 is driven in one direction by the shuttle wheel 16, and in the other direction by the other shuttle wheel 17, since the shuttle wheels turn in opposite directions, while the cam 31 attached to shaft 27 regulates the time intervals, during which one shuttle wheel or the other one is in mesh with the respective racks 42 or 43 attached to the underside of the type-bed 39 from the supporting slideways. The impression cylinder of the press is indicated by reference numeral 48.

In the end portions of the type-bed turning forks 49, 50 are arranged, into which engage swing arms 51, 52, respectively, driven by means of levers 54, 55, respectively, from gear wheels 11, 12, respectively. The inner ends of lever 54, 55 are pivotally connected with crank pins 53, 53' respectively, on gear wheels 11, 12. The free ends of arms 51, 52 suitably are provided with rollers 56, 57, respectively. The opposite ends of swing arms 51, 52 are pivotally mounted on brackets 58, 59 respectively,

secured to the machine frame. In this way, the type-bed is controlled in its turning movement (retardation, turning and acceleration periods. The beginning of mesh and release respectively after the acceleration period is effected while the type-bed has constant speed, in other words, during the printing and return periods.

The shape of the curve of the turning forks is so adapted that rollers 56, 57 of swing arms 51, 52, which performs an oscillatory movement along a circle shaped arc can be caught in the fork when it is moving at constant speed by moving upwards in same. The difference between the linear motion of the roller and the fork is compensated by the upward and backward movement of the roller in relation to the movement of the type-bed. The retardation force generated is taken up by the roller and is transmitted to driving gear wheel 8. This force brings about angular acceleration of the driving shaft, and, naturally, also of the other shafts in the system, but the degree of inequality can be made insignificant by a suitably dimensioned swing mass.

The retardation movement of the roller which is generated by a rotary motion will become harmonic or nearly harmonic, that is, the force varies in a linear manner with the travel. During the acceleration period, the energy stored in the flywheel (not shown) of the press is used for increasing the speed of the type-bed.

When studying the desirable curve shape of the turning fork it is found that there must be two different paths of motion for the roller center; one for entering and one for leaving. The motion is not quite symmetrical, as will be seen from Fig. 4.

When the roller enters the turning fork, the inner crank pin is at about 15° in front of point I, and the lever is in position A, Fig. 4. A small angular motion clockwise motion of point x along arc AC as a motion of the same size placed symmetrically after point II, situated 180° after point I.

The inner shape of the turning fork is shown in outline in Fig. 5 where R =roller radius. The distance "a" between the curves for in-and-outgoing motion will be, for instance, in a press for 100 cm. width of paper about 0.3 mm. at the entrance to the fork (the shuttle wheel in mesh with the rack) and decrease to 0 in the position corresponding to the beginning of the turning period, when the shuttle wheel is released from the rack. The roller thus lies in the fork without play during the turning movement.

That part of the curve which is working during the

turning period properly speaking can be straight with a larger or smaller inclination, when the turning movement will become harmonic with a turning path somewhat depending upon the inclination and a final force depending upon same as a consequence.

I claim:

In a printing press having a reciprocating type-bed provided with a pair of driving racks adapted to be alternatively driven by periodically meshing with driving shuttle wheels during the central parts of the movement of said type bed, and during the end portions of its movements, during retardation and acceleration is driven through turning forks attached to the type bed, said forks having legs spaced apart providing grooves therebetween which are engaged by swing arms having rollers which enter into grooves formed by the legs of said forks, the improvement residing in that said forks each consist of a single piece and are of such shape as to provide grooves limited by walls which are comprised of straight, parallel inner parts, and outer parts which curve outwardly, the centers of curvature of the curves of the said outer portions of the respective legs being on the same side of said slot so that said outer portions of said legs curve in the same direction, the radius of curvature of the curve of the outer portion of the leg on the side of said slot located closest to said centers of curvature being smaller than the radius of curvature of the curve of the outer portion of the one of said legs located farthest from said centers of curvature whereby said outer portions of said walls are divergent, the locations of said centers of curvature and the radii of curvature of the curves of the outer portions of said legs differing from each other in location and curvature respectively by an amount corresponding to the difference in the paths of said rollers when moving inwardly and outwardly of the portion of said slot formed between the outer curved portions of said walls of said legs.
